BLOCK FOR PLANTER AND WALL
CONSTRUCTIONS

Philip Adelman, 5821 E. Wardlow Road,
Long Beach, Calif. 90808

Filed Mar. 23, 1970, Ser. No. 22,021

Term of patent 14 years

Int. Cl. D25—01

U.S. Cl. D35—1

FIG. - 1

FIG. - 2

FIG. - 3

FIG. - 4

FIG. - 5

FIG. - 6

FIG. - 7

FIG. - 8

FIG. - 9

FIG. - 10

FIG. 1 is a perspective view of a block for planter and wall constructions showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a perspective view of a modified form of the block for planter and wall constructions shown in FIG. 1;

FIG. 7 is a top plan view of the modified form of FIG. 6;

FIG. 8 is a front elevational view of the modified form of FIG. 6;

FIG. 9 is a left side elevational view of the modified form of FIG. 6; and

FIG. 10 is a right side elevational view of the modified form of FIG. 6.

I claim:

The ornamental design for a block for planter and wall constructions, substantially as shown and described.
